UNITED STATES PATENT OFFICE.

ALEXANDER C. ENOCH, OF MOUNT PLEASANT, OHIO, ASSIGNOR OF ONE THIRD TO JAMES H. TURK, OF PLEASANTGROVE, OHIO.

CHURN.

SPECIFICATION forming part of Letters Patent No. 713,293, dated November 11, 1902.

Application filed April 2, 1902. Serial No. 101,089. (No model.)

To all whom it may concern:

Be it known that I, ALEXANDER C. ENOCH, a citizen of the United States, residing at Mount Pleasant, in the county of Jefferson and State of Ohio, have invented certain new and useful Improvements in Churns; and I do hereby declare the following to be a full, clear, and exact description of the invention, such as will enable others skilled in the art to which it appertains to make and use the same.

This invention has relation to churning and churn-power, the primary purpose being to operate the dasher at different rates of speed without varying the speed of the motive power, the body of the churn being adjustable and the churn-dasher having cog-gearing of different diameters adapted to mesh with the driver of the motive power, so as to operate the dasher at required speed.

The improvement consists, essentially, of the mountings for the churn-body whereby the latter is adjusted, the dasher-support adapted to interlock with the dasher and provided with the speed-gearing, and means for preventing longitudinal movement of the shaft supporting the dasher to prevent escape of any liquid from the opening through which the dasher-shaft passes.

The improvement further consists of the novel features, details of construction, and combinations of the parts, which hereinafter will be more particularly set forth, illustrated, and finally claimed.

In the drawings hereto attached and forming a part of the specification, Figure 1 is a side view of a churn and churn-power embodying the invention. Fig. 2 is a top plan view showing a portion only of the churn-power. Fig. 3 is a transverse section of the churn-body and the dasher, showing the dasher-shaft in full and the adjunctive parts co-operating therewith. Fig. 4 is a perspective view of the dasher and shaft, the parts being separated. Fig. 5 is a detail side view of the means for holding the dasher-shaft in position.

Corresponding and like parts are referred to in the following description and indicated in all the views of the drawings by the same reference characters.

The churn-power comprises a frame 1 and

a train of gearing adapted to be operated either by spring or weight power, or both, and comprises a driver 2, from which the power is taken for operating the dasher-shaft 3. 55 When weights are employed, curved arms 4 extend in opposite directions from the upper corners of the frame 1, and corresponding arms are jointed at their outer ends by a rod 5, upon which a grooved pulley 6 is free to 60 slide and turn and over which a cord or chain 7 passes and to the lower end of which is attached the weight 8. The curved arms 4 are adjustable, so as to elevate or lower the pulleys 6 and to throw the weights 8 to a greater 65 or less distance from the churn-power. Clamp-nuts 9 serve to secure the curved arms 4 in an adjusted position.

A stand 10 is located at one side of the churn-power and is provided at its ends with 70 cleats or flanges 11, extended upwardly and between which is placed the churn-body 12. Brackets or plates 13 are secured to opposite ends of the stand and receive set-screws 14, which pass through threaded openings in the 75 cleats or flanges 11 and serve to secure the churn-body upon the stand in an adjusted position. A bow-spring 15 is interposed between the inner end of the outermost set-screw and the adjacent end of the churn-body, so as to admit of a yielding outward movement of the churn-body to obviate any possible binding between the driver 2 and the elements of the speed-gearing 16, applied 80 to the outer end of the dasher 3. 85

The dasher is arranged to rotate about a horizontal axis and comprises a tubular center 17 and radial arms supporting transverse blades. The dasher is removably fitted within the churn-body and is mounted upon the 90 dasher-shaft 3, which passes through the tubular center 17 and obtains bearings in the sides of the churn-body. Interlocking means are provided between the dasher and dasher-shaft, because both rotate as one part and 95 may be of any formation, and, as shown, teeth 18 are provided at one end of the tubular center 17 to engage with corresponding teeth 19 at the inner end of an enlarged portion of the dasher-shaft 3. The dasher-shaft when 100 placed in position is held against longitudinal movement by means of pivoted plates 20,

adapted to enter a groove 21 in the enlarged end portion of the dasher-shaft. These plates 20 are pivoted to a side of the churn-body, and their meeting edges are notched to receive the grooved portion of the dasher-shaft, the free ends of the plates being secured together by a suitable catch or fastening means 22 and held from outward displacement by a keeper 23. These pivoted plates 20, in addition to holding the dasher-shaft from longitudinal movement, serve to prevent the escape of any liquid from the opening through which the dasher-shaft is passed.

15 The speed-gears *a* and *b* consist of cog-gearing of different diameters secured to the outer end of the dasher-shaft in any convenient way, either one being adapted to mesh with the cog-gearing of the driver 2. The 20 lateral and longitudinal adjustment of the churn-body enables any selected element *a* or *b* of the speed-gearing 16 to mesh with the driver 2. A proper adjustment of the set-screws 14 secures the churn-body in an 25 adjusted position. While the churn-power may run at a uniform speed, the dasher may be caused to run fast or slow by means of the speed-gearing 16, as will be readily comprehended.

30 The churn-body is adjusted or moved laterally by hand, the movement being such as to admit of one or the other of the gears *a* and *b* coming in the plane of the driver 2. The longitudinal adjustment may be effected 35 by proper movement of the set-screws 14 or by hand, as may be desired. After the churn-body has been properly adjusted it is secured, as stated, by means of the set-screws 14 and the bow-spring 15.

40 Having thus described the invention, what is claimed as new is—

1. In combination, a churn-power comprising a driver, a laterally and longitudinally adjustable churn-body, a dasher horizontally mounted in the churn-body, speed-gearing applied to the dasher-shaft and comprising a plurality of gears of different diameter and adapted to have a gear intermesh with the aforesaid driver, and means for securing the 45 churn-body in an adjusted position, substantially as specified.

50 2. In combination, a churn-power comprising

ing a driver, a laterally and longitudinally adjustable churn-body, means for securing the churn-body in an adjusted position, a 55 dasher movably fitted within the churn-body and adapted to rotate about a horizontal axis, a dasher-shaft movably fitted to the churn-body and adapted to support and interlock with the dasher, and speed-gearing at the 60 outer end of the dasher-shaft and adapted to have any one of the same comprising a plurality of gears of different diameter intermesh with the aforementioned driver, substantially as specified. 65

3. In combination, a churn-power comprising a driver, a laterally and longitudinally adjustable churn-body, means for securing the body in an adjusted position, a dasher removably fitted within the churn-body, a 70 dasher-shaft forming a support for and adapted to interlock with the dasher, speed-gearing at the outer end of the dasher-shaft comprising a plurality of gears of different diameter, one of said gears being adapted to intermesh with the aforesaid driver, and means applied to a side of the churn-body to prevent longitudinal movement of the dasher-shaft and prevent the escape of any liquid from the opening through which the dasher- 75 shaft is passed, substantially as specified. 80

4. In combination, a churn-power comprising a driver, a stand at one side of the churn-power, set-screws at opposite ends of the stand, a churn-body adjustable longitudinally 85 and laterally upon the stand and adapted to be held in an adjusted position by means of the set-screws, a spring between the churn-body and one of the set-screws to prevent binding of the gearing between the churn-power and dasher-shaft, a dasher arranged to operate within the churn-body, and speed-gearing applied to the dasher-shaft and comprising a plurality of gears of different diameter, one of said gears being adapted to intermesh with the aforesaid driver, substantially 90 as set forth. 95

In testimony whereof I affix my signature in presence of two witnesses.

ALEXANDER C. ENOCH. [L. S.]
